UNITED STATES PATENT OFFICE.

ABRAHAM I. ORLANSKY, OF CHARLESTON, SOUTH CAROLINA.

TOY.

1,116,911.

Specification of Letters Patent.

Patented Nov. 10, 1914.

Application filed August 1, 1914. Serial No. 854,497.

To all whom it may concern:

Be it known that I, ABRAHAM I. ORLANSKY, a citizen of the United States, and a resident of Charleston, in the county of 5 Charleston and State of South Carolina, have invented a new and Improved Toy, of which the following is a full, clear, and exact description.

This invention relates to improvements in 10 toys and more particularly to a game device for playing novel and amusing games requiring the exercise of skill and proving an amusement to old as well as young folks.

Another object of the invention is to provide a toy counting device which embodies a disk-like member mounted upon an endless strand of cord or the like passing through spaced openings in said member in such a manner that when the cord is twisted the 20 toy can be spun or caused to revolve, while by providing a novel arrangement of numbers on its peripheral edge and upon its opposite faces having coöperating pointers, games may be played requiring the exercise 25 of skill by bringing the member to a stop by causing it to contact with a surface, or when so stopped the pointer will coöperate with the numbers on the opposite faces to try for a certain number or character, a sum total or 30 to play the ordinary games played with dice.

With the above and other objects in view, the invention resides in the peculiar combination and arrangement of parts to be hereinafter more fully described, illustrated and 35 claimed, it being also an object to provide a device which is simple in construction, durable and efficient.

Reference is to be had to the accompanying drawings forming a part of this specification, in which similar characters of reference indicate corresponding parts in all the views and in which—

Figure 1 is a perspective view of my improved toy showing the manner of bringing the same to a stop, as when playing a game; Fig. 2 is a face view of the disk-like member with the cord in section; Fig. 3 is a sectional view taken on the line 3—3 of Fig. 2; Fig. 4 is a view similar to Fig. 2 but showing a modified form of attaching one of the pointers; Fig. 5 is a plan view of a strip showing the arrangement of the edge numerals or characters; Fig. 6 is a sectional view of a modification showing a different 45 manner of securing the cords to the disk so as to project from opposite sides thereof; Fig. 7 is a detail view of the securing member employed in connection with the form of the invention shown in Fig. 6; Fig. 8 is a face view showing a further modified way of attaching the cords; and Fig. 9 is a sectional view of the form of the invention 50 illustrated in Fig. 8.

As shown, the improved toy embodies a disk-like member 10 which more especially 55 consists of a relatively heavy or solid body made from various stuff such as candy, chewing gum, metal, wood, rubber, paper or glass, and preferably provided at its edge portion 11 with edge faces 12 produced by 60 making the disk hexagonal or any other multiple-cornered shape depending upon the nature of the play and the material from which the device is made. The disk is made solid or can be made up of a hollow box or 65 receptacle 13 filled with candy, gum, wood or the like to add novelty thereto from a standpoint of market value, and each disk is provided with a pair of spaced transverse 70 passages or apertures 14 adapted to receive 75 opposed portions of an endless string or cord 15 therethrough. The opposed faces of the disk are provided with numbers from 80 one to six, as indicated by the numeral 16, and these numbers are preferably carried by 85 opposed paper or covering sections 17 forming parts of the box if desired. The edge of the disk is covered by a strip 18 having indications such as zero, 1, 3/4, 1/2, 1/4 and 90 "Try again" in succession, as indicated by 95 the numeral 19, and are spaced apart so as to dispose one of these numbers or characters at each edge face of the periphery of the disk.

Fixed to the cord at opposite sides of the 95 disk and in close proximity to the faces thereof are pointers 20 preferably made from sections of sheet metal of such length as to extend as far as the edge of the disk and to point to the numbers or characters 100 16 between the division lines 21, equally dividing the opposed faces into the spaces occupied by these numbers. These pointers are adapted to turn with the cord when the latter is twisted by catching hold of the end 105 portions of the cord in the manner shown in Fig. 1 and twisting the cord by turning the disk, so that by exerting pull upon the ends of the cord and then releasing the same the disk will be caused to revolve in opposite directions and may be brought to a stop by 110 bringing it in sudden contact with a surface.

In this manner one of the characters on the edge faces of the disk may be brought upright or exposed to view upward, and by fixing a lucky number considerable skill may be exercised by the players in causing this number to be brought into the position named. In addition, the game may be played by spinning the disk in the manner specified and by causing the numbers 5
 10 characters to represent different points so that the highest number of points in a given number of trials or the like will win the game. When the zero mark appears upright the player is credited with a corresponding count, and so on, while if the words "Try again" appear another chance will be given to effect the stopping of the disk in such a manner as to cause one of the numbers of value to be disposed upward. 15
 20 In using the numbers upon the opposite faces the disk is spun or turned in the same manner and brought to a stop so that the needles or pointers carried by the cord on said opposed faces will be directed toward 25 certain of the numbers, whereby the games played with dice can be more easily played or the device in this manner used as a counter. This will be permitted since the cord may never be entirely unwound or 30 drawn entirely taut, and if so, this will only happen at different times and the pointer will thus be directed toward different numbers. As a modified manner of attaching the pointers the same may be constructed of 35 a single section of wire, as shown at 22 in Fig. 4 of the drawings, with one end rebent and clamped on the cord to bring the same together adjacent to the passages or apertures 14, as in the previously described 40 construction, while the pointers are retained in position by twisting one strand of the wire around the other, as shown at 23. By making the disk of glass or other transparent material the numbers on the opposite faces of the disk are rendered visible from 45 one side so that it is unnecessary to look at both sides or to strain the eyes in order to determine the count.

In the modification shown in Figs. 6 and 50 7 of the drawings the disk is of the same construction but in lieu of providing spaced passages or openings therethrough for receiving the cords so that the cords will project in opposite directions therefrom, a fastener 24 is employed, the same consisting of 55 a section of wire rebent at its ends as shown at 25 in the form of a double wire similar to the shape of a safety pin, and cords 26 are passed through the rebent ends after the 60 fastening member is anchored in the disk by permitting parts of the rebent ends to project from the faces of the disk through which the cords are threaded. These rebent ends thus produce eyes for receiving 65 the cords which project in the opposite di-

rections whereby the disk may be turned in the usual manner.

In the form of the invention shown in Figs. 8 and 9 the disk is made up of a shell as heretofore described of metal or paper and each side of the shell is provided with a pair of cuts or slits 27 which are spaced apart to provide intermediate portions 28 and the cords are passed beneath these portions and through the slits or punches near the center of the disk after the same are raised to provide ears. The cords are each in the form of loops.

Having thus described my invention, what I claim as new and desire to secure by Letters Patent is:—

1. A toy comprising a disk-like member, one or more endless strands having portions thereof engaged with said member and adapted to be twisted for spinning or revolving the same, characters on the edge and opposite faces of the disk, and pointers carried by the twisting strands adjacent the opposite faces of the disk-like member to coöperate with the characters when the disk is brought to a stop.

2. The combination with a disk supported by a cord and adapted to be turned, said disk having edge faces with a plurality of characters thereon and with characters on its opposed faces; of pointers carried by the cord adjacent to said opposed faces for co-operation with the characters on said faces when the disk is brought to a stop by contact with a surface, such stopping of the disk also causing one of the edge characters to show upward as and for the purpose described.

3. A toy game device, comprising a shell with a plurality of edge faces having characters thereon such as zero, 1, 3/4, 1/2, 1/4 and "Try again", said shell being filled to form a solid body and having spaced transverse passages, an endless strand with portions passed through said passages and adapted to be twisted by turning the body thus formed so that by alternately pulling and releasing strain upon the ends of the cord said body will revolve and may be brought to a stop by contact with a surface to dispose one of the edge characters to view.

4. A toy game device, comprising a shell with a plurality of edge faces having characters thereon such as zero, 1, 3/4, 1/2, 1/4 and "Try again", said shell being filled to form a solid body and having spaced transverse passages, an endless strand with portions passed through said passages and adapted to be twisted by turning the body thus formed so that by alternately pulling and releasing strain upon the ends of the cord said body will revolve and may be brought to a stop by contact with a surface to dispose one of the edge characters to view, the opposed faces of the shell being divided into spaces.

numbered from one to six, and pointers fixed to the cord to turn therewith adjacent to said faces for coöperation with said numbers to produce a counting device or permit the playing of games such as played with dice.

In testimony whereof I have signed my

name to this specification in the presence of two subscribing witnesses.

ABRAHAM I. ORLANSKY.
